CIGARETTE IGNITER AND DISPENSER

Frank C. Alumbaugh, St. Joseph, Mo., assignor to
Meyer N. Leibowitz, Philadelphia, Pa.

Application September 24, 1935, Serial No. 41,844

3 Claims. (Cl. 312—86)

An object of this invention is to provide an improved cigarette dispensing and lighting device.

A further object of the invention is to provide an improved cigarette dispensing and lighting device susceptible of complete operation through a single control member.

A further object of the invention is to provide an improved feeding mechanism operable to dispense cigarettes one by one from a magazine.

10 A further object of the invention is to provide improved cigarette igniting means in operative combination with a cigarette dispenser.

A further object of the invention is to provide an improved single control means operable to 15 selectively ignite and dispense cigarettes gravity-fed from a magazine.

A further object of the invention is to provide an improved operative combination of cigarette magazine, ash receiver, dispensing means 20 and igniting means in a single unit susceptible of facile mounting and operation.

A further object of the invention is to provide an improved cigarette dispensing and igniting device which is inexpensive of manufacture, positive 25 and efficient in operation and durable in use.

25 My invention consists in the construction, arrangement and combination of elements herein-after set forth, pointed out in my claims and illustrated by the accompanying drawing, in which:

30 Fig. 1 is a front view of the device, showing the position of the igniter and control knob; Fig. 2 is a side view showing the igniter mounting; Fig. 3 is a cross section taken on line 3—3 of Fig. 1; and Fig. 4 is a bottom view partly broken away to 35 show the interior construction.

In the construction of the improvement as shown, the numeral 1 designates a housing adapted to form the front, rear and side walls of a container which housing is rectangular in plan and 40 formed of sheet metal in any suitable manner, the upper and lower ends thereof being open. The rear wall 2 of the housing 1 may be formed integrally with the rest of the housing or may be a separate plate, as shown, fastened by means of 45 interengaging ears to side walls of the housing, the latter construction having merit from the standpoint of economy and facility of manufacture. A bracket 3 may be secured to the rear wall 2 in any suitable fashion and provides means whereby 50 the device may readily be attached to any convenient supporting structure such as an automobile instrument panel. The upper end of the housing 1 may be closed in any desired manner by a hinged or removable member, the closure member illustrated comprising a hollow cap 4 adapted

to be telescopically received within and frictionally held by the open end of said housing, a hole opening through the upper surface of the cap adapting the latter to use as an ash receiver. Within and substantially closing the lower end of the housing 5 1, a plane plate 5 is transversely disposed with its rear margin normally adjacent the rear wall of said housing and its surface inclining forwardly and downwardly toward the front wall of the housing. Ears 6 depend from each end of the 10 plate 5 adjacent side walls of the housing 1 and are engaged by screws 7 horizontally disposed through said side walls or through ears carried by the rear wall 2, thus pivotally mounting the plate 5 within and for limited oscillation relative to the 15 lower end of the housing. The forward margin of the plate 5 is spaced from the front wall of the housing 1 a distance sufficient to permit a cigarette to pass therebetween when said plate is in its rearmost position, and the material forming said 20 plate is bent downwardly at said forward margin, then rearwardly, then again downwardly for a space and finally curved forwardly to terminate in a free edge lying in substantially the same vertical plane with the forward margin first mentioned, thus forming an arcuate, depending flange or lip on and beneath the forward margin of the plate 5 and opening toward the front wall of the housing 1, as is clearly indicated at 8. The front wall of the housing 1 extends downwardly as far 25 as the lip 8 and is curved inwardly, as shown at 9, to provide a flange terminating in a free edge in closely spaced opposition with that of the lip 8, the flange 9 and lip 8 thus cooperating to form a cup in which may be received a single cigarette 30 from the magazine above the plate 5. The plate 5 is yieldingly held in its normal, rearmost position by means of leaf-springs 10 secured at their upper ends to the rear wall 2 of the housing and arranged with their free ends engaged through 35 slots adjacent the rear margin of the plate 5. Beneath the plate 5 and with its forward margin engaged in the curve formed on the forward margin of said plate is positioned a slide bar 11 which is held in place by means of ears 12 struck out of 40 the plate 5 and bent forwardly over the rear margin of said bar, thus mounting the bar for rectilinear reciprocation. One end of the bar 11 is bent downwardly and curved forwardly to terminate in obstructing relation with the cup-like 45 channel formed by the lip 8 and flange 9, as indicated in Fig. 4 at 13, and a knob-like handle 14 is fixed to the extension 13 and projects outwardly from the housing 1 through a notch in the lower, forward corner of one side wall thereof. The 50 55

arrangement thus far described completes the dispensing mechanism of the improvement. Cigarettes loosely stored in the magazine of the housing 1 rest on the inclined surface of the plate 5 and are fed forwardly by gravity to drop one by one into the channel defined by the lip 8 and flange 9 when said channel is unoccupied. With a cigarette in the channel, downward pressure on the handle 14 acts to tilt the plate 8 and its attached elements about the screws 7 and lower the free margin of the lip 8 below the free margin of the flange 9, thus permitting the cigarette positioned in the channel to escape and drop from its support, the same action bringing the forward margin of the plate 5 forwardly beneath the cigarettes remaining in the magazine and obstructing the throat leading to the channel until the plate is returned to its normal position. The springs 10 prevent the cigarettes from dropping behind the plate 5 as the latter is oscillated and the motion of said plate acts to agitate the cigarettes in the magazine and prevent packing or bridging thereof. The rear wall 2 of the housing 1 is extended forwardly and downwardly beneath the housing to terminate in a pair of spaced, upturned ears 15 positioned somewhat in front of the front wall of said housing, thus providing a carrier on which the cigarette discharged from the container may be received and held for convenient manual removal.

The igniter employed in the improvement forms part of a unitary assembly adapted for ready removal and replacement relative to that side of the housing 1 opposite the handle 14. As shown in Fig. 2, the igniter assembly comprises a base plate 16 adapted to overlie the rear lower corner of that side of the housing 1 opposite the handle 14 where it is intersected and clamped in position by a screw 7, interengaging ears carried by said plate and the housing serving to prevent rotation of the plate about said screw. Fixed to and insulated from the upper forward corner of the plate 16, an arm 17 extends forwardly to terminate in a shallow cup 18 opening toward and spaced outwardly from the adjacent end of the channel formed by the lip 8 and flange 9, an oblique brace 19 being insulated from and rigidly connecting the lower forward corner of the plate 16 with the cup 18 to securely position the latter. Within and insulated from the cup 18 is mounted a flat helix 20 of electrically-heatable material, one end of said helix being connected electrically with the brace 19 and the other end thereof being electrically connected with the cup 18, and a wire or suitable conductor 21 is operatively connected with the lower end of the brace 19 to complete one side of the circuit including the igniter. The switch controlling the igniter is formed as a part of the slide bar 11 and comprises a finger 22 formed on and projecting longitudinally from the end of said bar adjacent the igniter, the free end of said finger being positioned to contact at times against the arm 17 and said finger having a length such as to space its free end from the arm 17 when the bar 11 is at one limit of its travel. The bar 11 is normally held with its finger 22 out of contact with the arm 17 by means of a retractile coil spring 23 engaging between said bar and one of the ears 6 and its travel under the influence of said spring is limited by stops carried by said bar in position to engage against the guide ears 12, travel of the bar in the other direction being limited by contact of the finger 22 with the arm 17. When the improvement is mounted on an automobile having a "single wire" circuit the con-

ductor 21 is connected with one pole of the source of electrical energy and the metallic parts of the improvement connect by means of the mounting screw or bolt with metallic parts of the automobile to provide the other side of the circuit which may then be closed by contact of the finger 22 with the arm 17 to permit current to flow through the helix 20 and heat the latter. Where the circuit employed is of "double wire" type, the conductor 21 is connected with one pole of the source of energy and a second conductor is led from the other pole of the energy source to connection with the slide bar 11 or any metallic element of the improvement electrically associated with said bar.

With the elements of the improvement assembled and arranged as above described, a cigarette rests in the channel formed by the lip 8 and flange 9 so long as there are loose cigarettes in the magazine and the plate 5 is in its normal position. To ignite the cigarette prior to its discharge from the device, inward pressure is applied to the handle 14 and acts to move the slide bar 11 longitudinally to contact of its finger 22 with the arm 17, thus completing the circuit to the helix 20 and heating the latter. As the bar 11 is moved toward the igniter, the extension 13 engages against one end of the cigarette and moves the latter longitudinally into engagement of its other end with the heated convolutions of the helix 20, the circulation of air between the cup 18 and adjacent housing 1 developed by the heat generated by the helix 20 being sufficient to insure rapid lighting of the cigarette end. After the cigarette has been lighted, the bar 11 may be permitted to return under the influence of the spring 23 and downward pressure applied to the handle 14 to discharge the lighted cigarette against the ears 15 ready for smoking. It is to be noted that a single control is employed operable in two directions to accomplish both functions of the device, hence said control may be operated selectively to effect either or both the lighting and dispensing functions.

Since many changes in the specific form, construction and arrangement of the elements shown and described may be had without departing from the spirit of the invention, I wish to be understood as being limited solely by the scope of the appended claims rather than by any details of the illustrative showing and foregoing description.

I claim:

1. In a cigarette dispensing and igniting device, a housing, a chamber in said housing adapted to contain cigarettes, a pivotally mounted plate forming the bottom wall of said chamber and being arranged to tilt forwardly relative to said housing, a plurality of cutout portions depending from said bottom plate, a depending arcuate flange formed along the front edge of said plate and having a portion extending rearwardly thereunder, a slide bar movably supported by said cut out portions and said rearwardly extending flange portion, an abutment at one end of said slide bar positioned adjacent one end of the channel defined by the arcuate face of said flange, an igniter carried by said housing adjacent the opposite end of said channel, and means for moving said slide bar and abutment toward said igniter whereby a cigarette may be moved along said channel into contact with said igniter.

2. In a device of the character described, a housing arranged as a magazine for loose cigarettes, a tiltable bottom member in said housing formed with a depending, longitudinal flange ar-

- ranged to automatically isolate a single cigarette from said magazine, a normally inactive igniter carried by said housing adjacent one end of said flange, a bar mounted for reciprocation on and beneath said bottom member, a finger on one end of said bar arranged to contact said igniter mounting at times and energize the igniter, an offset on the other end of said bar arranged to contact the end of a cigarette in said flange and move the latter into end contact with said igniter, yielding means normally positioning said bar at the limit of its range of travel remote from said igniter, and a handle on the offset portion of said bar and extending without said housing, whereby said bar may be moved to simultaneously energize said igniter and contact a cigarette therewith, said handle being arcuately movable to tilt the bottom member for discharge of a cigarette from said flange.
3. In a cigarette dispensing and igniting device, a housing, a chamber in said housing adapted to contain cigarettes, a pivotally mounted plate forming the bottom wall of said chamber and being arranged to tilt forwardly relative to 5 said housing, a plurality of cutout portions depending from said bottom plate, a depending arcuate flange formed along the front edge of said plate and having a portion extending rearwardly thereunder, a slide bar movably supported 10 by said cutout portions and said rearwardly extending flange portion, an igniter carried by said housing adjacent one end of said flange, and means on said slide bar adjacent the other end of said flange for urging a cigarette into igniting 15 relation with said igniter.

FRANK C. ALUMBAUGH.
